UNITED STATES PATENT OFFICE.

WILLIAM A. SMITH, OF DENVER, COLORADO, ASSIGNOR TO INGERSOLL-RAND COMPANY, OF JERSEY CITY, NEW JERSEY, A CORPORATION OF NEW JERSEY.

IMPACT-ENGINE.

1,338,259.

Specification of Letters Patent. Patented Apr. 27, 1920.

Application filed December 26, 1917. Serial No. 208,755.

To all whom it may concern:

Be it known that I, WILLIAM A. SMITH, a citizen of the United States, residing at Denver, in the county of Denver and State of Colorado, have invented certain new and useful Improvements in Impact-Engines, of which the following is a specification.

My invention relates to improvements in impact engines of the type in which a reciprocating hammer or piston is operated by fluid pressure to deliver a rapid succession of blows upon a cutting tool at the front end of a housing in which the piston has its movement.

It is the primary object of the present invention to provide a novel method of admitting the compressed air or other motive fluid used in the operation of the impact engine, to the working faces of its reciprocating piston and of exhausting the same at the proper periods, whereby to obtain the maximum efficiency in ratio to the impelling force of the motive fluid.

I attain this object by the construction and arrangement of parts shown in the accompanying drawings in the two views of which corresponding parts are designated by like reference characters, and in which—

Figure 1 represents a longitudinal section of my improved impact engine with the piston at the beginning of its active, forward stroke, and

Fig. 2, a similar section with the piston in the position it occupies at the time it comes in impellent engagement with the cutting tool at the forward end of the housing in which it has its movement.

In the drawings, the reference numeral 2 designates the housing of the impact engine, 3 the piston or hammer which has a reciprocating movement therein, and 4 the cutting tool which is longitudinally slidably fitted in a keeper 5 at the front end of the housing, and projects within the same to be engaged by the piston during its active stroke.

The housing has a piston-way composed of a primary pressure chamber 8 intermediate of two end-chambers 6 and 7 of reduced diameter.

The piston of the impact-engine is composed of an oblong body, the end portions of which provide heads 9 and 10 which are slidably fitted in the end chambers of the piston-way.

The piston has intermediate of its ends,

an integral head 12 of enlarged diameter which is fitted for reciprocation in the primary pressure chamber and it has between its said end-portions and its enlarged head, annular grooves 13 and 14 which provide channels for the passage of motive fluid to the different chambers, as will hereinafter be more fully described.

The channels of the piston are spaced from the head 12 to provide at opposite sides thereof, shoulders 15 and 16 which upon entering the end chambers of the piston-way at the ends of the piston-strokes, produce air-cushions to deaden the impact of the parts.

The chamber 6 of the piston-way at the forward end of the housing opens into an enlarged closed space 17 into which the rear end of the cutting tool projects, and serves in the operation of the engine to guide the forward portion of the piston in its reciprocating motion to and from the tool.

The chamber 7 at the rear end of the housing, which will hereinafter be referred to as the auxiliary pressure-chamber, is adapted to communicate directly with the atmosphere by an exhaust port 18 and a therewith connecting annular groove instead of indirectly through one of the other working chambers in the tool, and the primary pressure-chamber 8 connects with the atmosphere by means of an independent exhaust port 19 which likewise is connected with an annular depression in the chamber-wall to expedite the direct discharge of spent fluid.

The air or other fluid under pressure used in the operation of the engine, enters the housing through an inlet 20 which by means of passages 21 and 22 is in continuous communication with ports 23 and 24 in the end-chambers of the piston-way adjacent their junctures with the primary pressure-chamber, and the auxiliary pressure-chamber 7 has two ports 25 and 26 connected by a by-pass 27 and located respectively rearwardly of and adjacent to the admission-port 23 and at the rear end of the chamber.

All the ports hereinbefore mentioned, connect with annular grooves in the chamber-walls to expedite and facilitate the passage of motive-fluid.

The exhaust-port 19 of the primary pressure-chamber is located so as to connect alternately with the spaces of the chamber at opposite sides of the piston-head 12 during the reciprocating movement of the pis-

80

ton, and the exhaust-port 18 of the auxiliary pressure-chamber 7 is covered by the respective end-portion 10 of the piston until the piston nears the end of its forward stroke 5 at which it engages the cutting-tool as shown in Fig. 2 of the drawings.

At the finish of the idle piston stroke, the ports 23 and 25 are in register with the rearward piston-channel 13 to admit motive fluid 10 simultaneously at corresponding ends of the primary and auxiliary piston-chambers, as shown in Fig. 1 of the drawings.

When the piston approaches the end of its active stroke, these ports are covered by 15 the head 10, and the channel 14 comes in register with the forward admission-port 24 to admit motive fluid to the space of the primary pressure-chamber forward of the head 12, for the return movement of the piston.

20 With the piston in this position the exhaust-port 18 of the auxiliary pressure-chamber is uncovered and the independent exhaust-port 19 communicates with the space of the primary pressure-chamber rearward of the piston-head 12.

In the operation of the engine, air under pressure, or other motive-fluid, enters the housing through the inlet 20.

Premising that the piston is at the beginning 30 of its forward or active stroke, as shown in Fig. 1, the channel 13 of the piston connects the admission-port 25 with the piston chamber 8 and with the port 23 to admit motive fluid simultaneously to the rear end 35 of the primary pressure-chamber and, by means of the by-pass 27, to the corresponding end of the auxiliary pressure chamber.

The exhaust-port 18 of the auxiliary pressure-chamber is at the same time covered 40 by the respective end-portion of the piston and the exhaust port of the large piston-chamber communicates with the space thereof forward of the piston-head 12.

The piston is driven forwardly by the 45 pressure of the motive-fluid thus admitted to its working faces at the corresponding ends of the heads 12 and 10, until its rear end-portion uncovers the exhaust-port 18 and its head 12 has moved past the exhaust port 19, at which time the ports 23 and 25 are covered by the head 10, and the forward admission-port 24 is placed in communication 50 with the forward end of the primary pressure-chamber by registration with the piston-channel 14.

The piston after having reached this position continues its forward motion by its inertia until the forward shoulder 15 enters the guide-chamber 6, at which point its motion 60 is reversed by the action of the compressed fluid in the forward portion of the large pressure-chamber upon the forward working face of the piston-head 12.

At the end of each stroke of the piston, 65 the rearward shoulder 16 momentarily en-

ters the rear pressure-chamber 7 thereby providing an air-cushion in the rearward space of the large chamber auxiliary to that simultaneously produced in the other pressure-chamber.

Having thus described my invention what I claim and desire to secure by Letters-Patent is:

1. An impact-engine comprising a housing having primary and auxiliary piston-chambers, ports for the admission of motive fluid at corresponding ends thereof and independent ports in said chambers for the exhaust of fluid directly from said chambers, and a tool-operating piston in said housing having working faces in said chambers and controlling the fluid-passage through said admission and exhaust ports, the piston being adapted to establish communication between the chambers and the respective exhaust-ports at the finish of its active stroke and to uncover the admission ports at the finish of its idle stroke for the admission of fluid to the chambers. 75

2. An impact-engine comprising a housing having primary and auxiliary piston-chambers, ports for the admission of motive-fluid at corresponding ends thereof and 80 independent ports in said chambers for the exhaust of fluid directly from said chambers, and a tool-operating piston in said housing having working-faces in said chambers and controlling the fluid-passage through said admission and exhaust ports, the piston being adapted to establish communication between the chambers and the respective exhaust ports at the finish of its active stroke and to uncover the admission ports at the finish of its idle stroke for the admission of fluid to the chambers. 85

3. An impact-engine comprising a housing having primary and auxiliary piston-chambers, ports for the admission of motive fluid at corresponding ends of the primary chamber, a port for the admission of motive fluid at one end of the auxiliary chamber and 95 independent ports for the exhaust of fluid from the chambers, and a tool-operating piston in the housing, having a piston-head in the primary chamber and an auxiliary working face in the auxiliary chamber and controlling the fluid-passage through said ports, the piston being adapted to uncover the admission ports at the finish of its idle stroke for the admission of fluid to the chambers, and the piston having a shoulder which cushions the idle stroke by entering the auxiliary piston-chamber. 100

4. An impact-engine comprising a housing having primary and auxiliary piston-chambers, ports for the admission of motive fluid at opposite ends of the primary chamber, a port for the admission of motive fluid at one end of the auxiliary chamber and independent ports for the exhaust of fluid from the chambers, and a tool-operating piston in the housing, having a piston-head in the primary chamber and an auxiliary working face in the auxiliary chamber and controlling the fluid-passage through said ports, the piston being adapted to uncover the admission ports at the finish of its idle stroke for the admission of fluid to the chambers, and the piston having a shoulder which cushions the idle stroke by entering the auxiliary piston-chamber. 110

5. An impact-engine comprising a housing having primary and auxiliary piston-chambers, ports for the admission of motive fluid at opposite ends of the primary chamber, a port for the admission of motive fluid at one end of the auxiliary chamber and 115 independent ports for the exhaust of fluid from the chambers, and a tool-operating piston in the housing, having a piston-head in the primary chamber and an auxiliary working face in the auxiliary chamber and controlling the fluid-passage through said ports, the piston being adapted to uncover the admission ports at the finish of its idle stroke for the admission of fluid to the chambers, and the piston having a shoulder which cushions the idle stroke by entering the auxiliary piston-chamber. 120

6. An impact-engine comprising a housing having primary and auxiliary piston-chambers, ports for the admission of motive fluid at opposite ends of the primary chamber, a port for the admission of motive fluid at one end of the auxiliary chamber and independent ports for the exhaust of fluid from the chambers, and a tool-operating piston in the housing, having a piston-head in the primary chamber and an auxiliary working face in the auxiliary chamber and controlling the fluid-passage through said ports, the piston being adapted to uncover the admission ports at the finish of its idle stroke for the admission of fluid to the chambers, and the piston having a shoulder which cushions the idle stroke by entering the auxiliary piston-chamber. 125

ber in communication with the spaces of said chamber at opposite sides of the piston-head.

4. The combination with an impact-engine in which a piston has working faces in two chambers of different diameters, and controls the passage of motive fluid through ports connecting with said chambers, of a passage uncovered by the piston at the finish of its idle stroke for the admission of fluid at an end of the smaller chamber, a port in said smaller chamber independent of the larger chamber and adapted to be uncovered by the piston at the finish of its active stroke for the exhaust of fluid from said chamber, and a separate exhaust port for said larger chamber.

5. The combination with an impact-engine in which a piston has working faces in two chambers of different diameters, and controls the passage of motive fluid through ports connecting with said chambers, of a passage uncovered by the piston at the finish of its idle stroke for the admission of fluid at an end of the smaller chamber, a port in said smaller chamber independent of the larger chamber and adapted to be uncovered by the piston at the finish of its active stroke for the exhaust of fluid from said chamber, a shoulder on the piston which cushions the idle stroke of the piston by entering said smaller chamber, and a separate exhaust port for said larger chamber.

6. An impact-engine comprising a housing having primary and auxiliary piston chambers, a port in connection with a fluid-inlet to admit motive fluid at an end of the primary chamber, a passage for the admission of fluid at the corresponding end of the auxiliary chamber and independent ports in said chambers for the exhaust of fluid directly from the chambers, and a tool-operating piston having piston-heads working in said chambers, and between said heads, a channel which co-operates with the heads to control the fluid passage through said ports, said channel connecting said admission-port with the primary chamber and with said passage for the simultaneous admission of motive fluid at corresponding sides of the piston-heads at the finish of the idle piston-stroke, and the head in the auxiliary chamber uncovering the independent exhaust port for said chamber at the finish of the active piston stroke.

7. An impact-engine comprising a housing having a primary piston-chamber, a piston-guide chamber and an auxiliary piston chamber respectively at opposite ends thereof, a fluid-inlet, ports connected therewith for the admission of fluid at opposite ends of the primary chamber, a passage to admit fluid at an end of the auxiliary chamber, and independent ports in said chambers for

the exhaust of fluid directly from the chambers, and a piston having heads working in said chambers and between said heads, channels which co-operate with the heads to control the fluid-passage through said ports, the channel between the heads in the primary and auxiliary piston-chambers connecting one of said admission-ports with an end of the primary chamber and with said passage for the simultaneous admission of fluid at corresponding ends of said chambers at the finish of the idle piston-stroke, and the channel between the head in the primary chamber and the head in the guide-chamber connecting the other admission-port with the opposite end of the primary chamber at the finish of the active piston-stroke while the piston-head in the auxiliary piston-chamber uncovers the independent exhaust-port for said chamber.

8. An impact-engine comprising a housing having primary and auxiliary piston chambers, a port in connection with a fluid-inlet to admit motive fluid at an end of the primary chamber, a passage for the admission of fluid at the corresponding end of the auxiliary chamber and ports for the exhaust of fluid from the chambers, and a tool-operating piston having piston-heads working in said chambers, and between said heads a channel which co-operates with the heads to control the fluid-passage through said ports, said channel connecting said admission-port with the primary chamber and with said passage for the simultaneous admission of motive fluid at corresponding sides of the piston-heads at the finish of the idle piston-stroke, and the head in the auxiliary chamber uncovering the respective exhaust port at the finish of the active piston-stroke, there being a shoulder between said channel and the head in the primary chamber which cushions the idle stroke of the piston by entering the auxiliary piston-chamber at the finish of said stroke.

9. An impact engine comprising a housing having a primary piston-chamber, respectively at opposite ends thereof a piston-guide-chamber and an auxiliary piston-chamber, a fluid-inlet, ports connected therewith for the admission of fluid at opposite ends of the primary chamber, a passage to admit fluid at an end of the auxiliary chamber, and independent ports in said chambers for the exhaust of fluid directly from the chambers, and a piston having heads working in said chambers and between said heads, channels which co-operate with the heads to control the fluid-passage through said ports, the channel between the heads in the primary and auxiliary piston-chambers connecting one of said admission-ports with an end of the primary chamber and with said passage for the simultaneous admission of fluid at corresponding ends of said chambers.

bers at the finish of the idle piston-stroke, and the channel between the head in the primary chamber and the head in the guide-chamber connecting the other admission-port 5 with the opposite end of the primary chamber at the finish of the active piston-stroke while the piston-head in the auxiliary piston-chamber uncovers the independent exhaust-port for said chamber, there being 10 shoulders at opposite sides of the head in the primary chamber which cushions the piston-strokes by entering the other chambers at the finish of the same.

10. An impact-engine comprising a housing having a primary piston-chamber, at an 15 end thereof an auxiliary piston-chamber of reduced diameter, a fluid-inlet, an admission port in the auxiliary chamber adjacent its juncture with the primary chamber, and in- 20termittently in connection with said inlet a

second admission-port adjoining the first-mentioned port, a by-pass connecting the second port with an end of the auxiliary chamber, and separate ports for the exhaust of fluid from the chambers, and a piston having 25 heads working in said chambers and between said heads, a channel which coöperates with the heads to control the fluid-passage through said ports, said channel connecting the first-admission-port with the primary chamber and with the second admission-port for the simultaneous admission of motive fluid at corresponding sides of the piston-heads at the finish of the idle piston-stroke and the head in the auxiliary chamber 30 uncovering its respective exhaust-port at the finish of the active piston-stroke.

In testimony whereof I have affixed my signature.

WILLIAM A. SMITH.
